HEEL-SHAPING MACHINE

Application filed January 17, 1927. Serial No. 161,529.

The invention to be hereinafter described relates to a machine for shaping heels and more particularly to a machine for shaping the breasts and shanks of wooden heels of 5 ladies' shoes.

In the manufacture of these wooden heels blocks are formed by making transverse cuts at intervals through a strip of wood which is square or oblong in cross-section, alternate 10 cuts being perpendicular and oblique to the length of the strip. Then a portion of each block is sawed away preliminarily to form the breast of the heel and the under face of the shank of the heel. The breast and face are 15 then sandpapered down by hand to give the under face of the shank convex form and to produce the curvature at the juncture of the breast with the shank. These are slow operations and frequently result in crude im- 20 perfect work.

The purpose of the present invention, therefore, is to provide an efficient machine whereby the breast of the heel and the convex face of the shank of the heel may be 25 quickly and perfectly formed.

The character of the invention may be best understood by reference to the following description of one good form thereof shown in the accompanying drawings, wherein:

Fig. 1 is a perspective view of a machine embodying the invention;

Fig. 2 is a front elevation of the machine;

Fig. 3 is a perspective view of details to be referred to;

Fig. 4 is a vertical section through the machine;

Fig. 5 is a front elevation of the table and apron carrying the same and showing the means for indicating the vertical adjustments 40 of the table for heels of varying sizes;

Fig. 6 is a perspective view of a heel block;

Fig. 7 is a perspective view of the block after the breast of the heel and the convex face of the shank of the heel have been formed by 45 the machine; and

Fig. 8 is a perspective view of a heel showing its final shape.

Referring to the drawings, a typical heel block 1 (Fig. 6) has a face 3 formed by a cut through the wooden strip perpendicular to

the length thereof, and an inclined face 5 formed by a cut through the strip oblique to the length thereof. The function of the present machine is to shape the block 1 to form the breast 7 (Fig. 7) of the heel and the convex 55 face 9 of the shank of the heel, and to form the proper curvature at the juncture of the breast with the face. In another machine the block is turned to give its back and sides the curved contour indicated at 13 (Fig. 8). 60

The machine shown herein as one good form of the invention comprises a rotary cutter 15 (Figs. 1, 2 and 4) having teeth 17, each formed to present a side cutting edge 19 and an end cutting edge 21, said edges having 65 a contour suitable for removing stock from the block and shaping the breast and face of the shank of the heel and with proper curvature at the juncture of the breast with the face. The cutter is mounted fast on a shaft 70 23 which may be conveniently the shaft of an electric motor 25 mounted on and secured to a bench 27.

A support is provided for holding the heel block in position to be acted upon by the cutter, and adjustments are provided to enable the machine to operate on blocks of different sizes and to make the cuts required for heels of different styles. 75

The support, in the present instance comprises a plate 29 (Fig. 1) which may be secured by screw bolts to the front end of the electric motor, said plate having a hole therein through which the cutter shaft passes. Projecting from the plate 29 are a pair of 85 cheeks 31 (Figs. 1 and 3) carrying arms 33 connected to the cheeks by screw bolts 35 entered through bores in the arms and threaded in holes in the cheeks.

It is desirable that these arms shall be adjustable horizontally and vertically. To accomplish this, intermediate plates 37 (Figs. 1, 2 and 3) are interposed between the cheeks and arms. Said cheeks have horizontal keys 39 fitting into horizontal grooves 41 in the 95 cheeks, and said plates have vertical keys 43 fitting into vertical grooves in the arms. The intermediate plates have apertures 45 therein sufficiently large to allow the necessary horizontal and vertical adjustments of 100

the arms. On release of the screw bolts 35, the arms may be adjusted horizontally or vertically as desired, and then the screw bolts may be set up to hold the arms in the positions 5 to which they have been adjusted.

The arms carry a hanger plate 47 (Figs. 1, 2 and 4) having a boss 49 at the upper end thereof interposed between the arms 33 and connected thereto by a through bolt 51. The 10 hanger plate has a guideway 53 (Fig. 4) receiving a slide 55 from which projects a pivot stud 57 extending into a bore in a slide 59 in a guideway 61 of an apron 63 located directly in front of the hanger plate 47. The 15 rear face of the slide 59 engages a pair of in-turned flanges 64 in the guideway. To hold the apron onto the pivot stud 57, the latter is provided with a reduced threaded end 65 receiving a nut 67 in a counterbore 69 in the 20 slide, said nut being adapted to be adjusted by a suitable spanner wrench. Projecting from the slide 55 oppositely to the stud 57, is a threaded stud 71 provided with an adjusting nut 73 and a lock nut 75. A plate 77 is 25 carried by the stud 71 and engages the rear face of the hanger plate, a spring washer 79 being interposed between the adjusting nut 73 and the plate 77. The construction is such that the nuts 73 and 75 and the spring 30 washer 79 will operate through the slide 55 and the slide 59 to hold the apron closely against the front face of the hanger plate, thereby to prevent any lost motion between them.

35 It is desirable that the slides 55 and 59 shall be adjustable in order to vary the distance of the pivot pin 57 from the cutter.

To accomplish this, a screw shaft 81 is threaded to the slide 55. Its upper end 83 is 40 entered into a bearing in the upper end of the hanger plate, and its lower portion 85 is mounted in a bearing at the lower end of the hanger plate. A collar 87 is secured by a pin to the screw shaft and engages the upper 45 end of the lower bearing to prevent movement of the screw shaft downward in the hanger plate.

A screw shaft 89 is threaded into a socket in the apron slide 59, and is mounted in a 50 bearing 91 in the apron. A collar 93 is secured by a pin to the screw shaft 89 and rests against the upper end of the bearing 91 and prevents movement of the screw shaft downward in the apron. To rotate the screws and adjust the slides, a gear 95 is provided on a sleeve 97 on the screw shaft 81 and connected to rotate therewith by a 55 spline 99. Fast on the lower end of the sleeve is a hand wheel 101. A gear 103 is secured 60 on the lower end of the screw shaft 89. The construction is such that the gear 95, sleeve 97 and hand wheel may drop downward until limited by engagement of the sleeve with a head on the screw shaft 85. In this position 65 the gear 95 is out of mesh with the gear

103. When it is desired to effect the adjustments of the screws and slides, the hand wheel is thrust upward to bring the gear 95 into meshing relation with the gear 103. Then turning of the hand wheel will rotate both 70 of the screw shafts and effect adjustment of the slides. Since the intermeshing gears will rotate in opposite directions, the screws are oppositely threaded to compensate therefor. The apron slide is carried by the pivot stud 75 57, and the screw shaft 91 depends from the slide and carries the apron. When the slides are adjusted, the screw shaft 91 will vary the distance between the apron slide and the lower end of its guideway, and thus the slide 80 adjustments will not vary the distance of the apron from the cutter.

The apron carries an inclined table 105 (Figs. 1, 2, 4 and 5) provided with a boss 107 in a fork 109 at the upper end of the apron, 85 said boss being connected to the arms of the fork by a bolt 111 entered through the arms and the boss.

To support the table in different positions of angular adjustment, a pair of links 113 are 90 provided having outwardly bent ends 115 (Figs. 1 and 2) pivotally mounted on screw bolts 117 secured to the apron. In the upper ends of the links are elongated slots 119 receiving screw bolts 121 threaded into the 95 outer end of the table. The construction is such that on release of the screw bolts 121, the table can be tilted to the position desired, and then the screw bolts may be set up, thereby to 100 secure the table in the position to which it has been adjusted. The table is adapted to support the block 1 and is provided with a stop or ledge 123 adapted to be engaged by the lower portion of the front face 3 of the block, as will be noted in Fig. 4. To position and 105 hold the block on the table, a pair of jaws 125 are pivotally mounted on pins 127 carried by ears 129 projecting from the table. The jaws have arms 131 projecting downward from the pins carrying screws 133 (Figs. 1 and 2) threaded into holes in the arms, and clamped in different positions of adjustment by screws 135 in split end portions of the 110 arms.

Suitable means is provided for rocking the 115 arms on their pivot pins to move the jaws toward each other to grip opposed sides of the heel block, and to move the jaws away from each other to release the block. This means in the present instance, comprises a cam in 120 the form of a wedge 137 (Figs. 2 and 4) which projects from the hub 139 of a stem 141 received by and secured to a tubular handle 143, said hub being mounted on a pin 145 carried by a pair of ears 147 depending from the 125 under side of the front end of the table. The wedge has front inclines 149 and rear inclines 151 and parallel faces 153 (Fig. 2). The construction is such that when the handle is 130 rocked to the left (Figs. 1 and 4) the front

inclines 149 will act on the screw bolts 133 and rock the jaws toward each other with a preliminary movement so as to shift the heel block laterally on the table and properly center the same. When the handle is rocked further to the left, the inclines 151 will act on the screw bolts 133, thereby causing the jaws to bite into and grip the block. Still further rocking of the handle to the left will bring the parallel faces 153 between the screw bolts, and thereby hold the jaws securely in their block gripping positions. Adjustment of the screw bolts 133 will set the jaws at varying distances apart in order that they may be adapted to heel blocks of different sizes. The jaws are urged away from each other by a coil spring 154 attached to the ends of the arms. To release the jaws from the block, the handle is rocked to the right, thereby causing the inclines of the wedge to wipe past the screws and allow the spring 154 to move the jaws and release the heel block.

It is desirable that further provision shall be had for holding the heel block on the table. To accomplish this, a presser, in the present instance in the form of a screw 155 (Figs. 1 and 4) is provided, said screw being mounted in a threaded hole in a lever 157 pivotally mounted intermediate its ends on a pin 159 carried by ears 161 standing up from the outer end of the table. The screw 155 is provided with a handle 163, and may be adjusted to conform to heel blocks of different sizes. The upper end of the lever 157 is split and provided with a screw 165 which may be adjustable to cause the split portions of the end of the lever to clamp and secure the screw 155 in the positions to which it is adjusted.

The lower end of the lever 157 is in the form of a toe 167 (Fig. 4) cooperating with a cam 169 formed on the handle 139, referred to. At the lower end of the cam is a notch 171. The construction is such that after the heel block has been centered on the table by the jaws as described, on rocking of the handle to the left, the cam 169 will wipe against the toe 167, thereby pressing the screw 155 against the back of the heel block and holding the front face of the block firmly against the stop 123 referred to, on the table. When the presser is moving to the back of the heel block parallel faces between the inclines 149 and 151 of the wedge are sliding past the screws 133 of the jaw arms. The gripping of the block by the jaws occurs after the presser is moved to the block.

A coil spring 173 has one end connected to a pin 175 on the lever 157 and its opposite end connected to a pin 177 on the handle, said spring serving to press the toe 167 against the face of the cam and toward the notch 171. When the handle is rocked to the right to release the jaws from the block, the cam will wipe along the toe, and the latter will drop into the notch under the influence of the

spring 163. This will cause the lever 157 and presser 155 to rock and release the back of the heel block.

It is desirable to provide means for making a pair of marks or indentations on a face of the heel block to serve as indexes assisting proper location of the heel block in the machine for turning the curved sides and back of the heel to the form shown in Fig. 8. To accomplish this, a pair of marker pins 179 (Fig. 4) are provided entered through holes 181 in the table, said pins being secured to a back 183 beneath the table engaged by a finger 185 projecting from the wedge 137 referred to. The construction is such that after the handle is rocked to move the wedge inclines 151 past the screws 133 and cause the jaws to grip the heel block, the finger 185 will lift the back 183 and press the marker pins 179 upward, thereby causing them to make a pair of indentations in the block.

It is desirable to provide means for limiting the rocking of the table and the apron carrying the same, and to accomplish this, the apron is provided with a stop in the form of a screw 187 (Figs. 2 and 4) received by an arcuate groove 189 in the face of the hanger plate and flaring toward the ends thereof. The table and apron may be rocked in opposite directions until limited by engagement of the stop 187 with the ends of the arcuate groove. The groove is formed flaring toward the ends thereof to allow the apron to rock about the axis of the pivot stud 57 when the radial distance of said axis from the stop 187 is varied.

To indicate the vertical adjustments of the pivot stud, the apron may have a scale 199 marked thereon adjacent one side of the guideway 61, and cooperating with a pointer 201 projecting from the slide 59. The scale has graduations numbered 3 to 11 corresponding to the usual eight different sizes of wooden heels. Knowing the size of the heel, the operator may readily adjust the slide 59 so that the pointer is opposite the graduation having a number corresponding to the number of the heel of the selected size, and then the table will be at the proper elevation to give the shank a convex curvature of the required radius.

In operation, the operator grasps the handle and rocks the table and apron to the right (Fig. 1) about the axis of the pivot stud 57. Then the table is ready to receive the block 1 which is placed thereon and secured by the jaws and presser as described. Then the operator rocks the table and apron to the left (Fig. 1) about the axis of the pivot stud, and in the course of this movement the rotary cutter will remove stock from the block 1 and shape the breast 7 and convex face 9 of the shank of the heel, and with the curvature 11 connecting them, as indicated in Fig. 7. Then the block is released and dis-

charged from the table and the latter is rocked back to the right where it is in readiness to receive the next block to be shaped.

- When the table is rocked to its position for 5 the cutter to commence its operation on the heel block, one edge of the table will be nearer the cutter than the other edge thereof, and at the end of the rocking movement, feeding the heel past the cutter, the other edge of the 10 table will nearer the cutter. In the course of this feeding movement, the table will vary its distance from the axis of the cutter, and thus the convex face 9 of the shank of the heel is formed.
- 15 In different styles of heels the angle between the breast and the shank varies, and therefore when heel blocks of such varying character are mounted on the table, the angle of the latter needs to be adjusted. This may be readily 20 accomplished by releasing the screw bolts 121 in the elongated slots 119, adjusting the table to the angle required, and securing the same by setting up said screw bolts. If the downward inclination of the table is increased, it will be moved downward and forward somewhat relatively to the cutter, but since the shanks should always have the same thickness, it is necessary to adjust the table 25 bodily upward and rearward to compensate for said movements relatively to the cutter. This may be readily accomplished by adjusting the ears 33 upward and rearward as permitted by the keys on the intermediate plates 37.
- 30 The pivot stud 57 should be adjusted vertically toward or from the cutter for heel blocks of different sizes. This is accomplished by adjusting the hanger plate and apron slides as described. The longer the radius 35 from the center of the pivot stud 57 to the cutter, the longer will be the radius of the curved face 9 of the heel shank.

In some styles of heels it is desired that the breast shall be flat, and in others that it shall 40 be concaved somewhat as shown in Fig. 7. When the hanger plate is adjusted so that it stands in vertical position, the cutter will produce a flat breast, and when the hanger plate is rocked to the left (Fig. 4) from the 45 vertical position, the cutter will form a concaved breast, the degree of the concavity being proportional to the extent of the inclination of the hanger plate. This adjustment of the hanger plate is accomplished by releasing the bolt 51, rocking the plate to the 50 position required, and then setting up the bolt.

By our invention a machine is provided 55 capable of quickly and perfectly forming the breast of the heel and the convex face of the shank of the heel. It does not require skilled labor to operate the machine. It is merely necessary that he shall move the handle rearward to secure the heel block to the table and 60 pull the handle forward to release and dis-

charge the heel block from the table, and it is necessary that he shall rock the handle in a plane transverse to that in which the handle is rocked as stated above, in order to feed the heel block past the cutter and return the 70 table to position for receiving the next heel block. Thus, these operations are all accomplished by one and the same handle. The adjustments of the machine are simple and easily made to adapt it for operating on heel 75 blocks of different sizes and styles.

It will be understood that the invention is not limited to the specific embodiment shown, and that various deviations may be made therefrom without departing from the spirit 80 and scope of the appended claims.

What is claimed is:—

1. A machine for shaping the breast and a convex face of the shank of a wooden heel, comprising, in combination, a rotary cutter 85 having external teeth formed to shape the breast and convex shank face, means for holding a heel block in position to be acted upon by the cutter, and means to rock and feed the heel block past the cutter and in a plane trans- 90 verse to the axis of the cutter, thereby to remove stock from the block and shape the breast and convex shank face.

2. A machine for shaping the breast and a convex face of the shank of a wooden heel, 95 comprising, in combination, a rotary cutter having external teeth formed to shape the breast and a convex face of the shank, a support, a table, means pivotally connecting the table to the support, means for securing a heel block on the table, means for moving the table about the point of pivotal connection of the table with the support and in a plane transverse to the axis of the cutter, thereby to feed the block past the cutter and shape the 100 breast and convex face of the shank.

3. A machine for shaping the breast and a convex face of the shank of a wooden heel, comprising, in combination, a rotary cutter having external teeth formed to shape the 110 breast and a convex face of the shank, a table for supporting a heel block, a pair of jaws pivotally mounted on the table and having arms projecting therefrom, a handle pivotally connected to the table, and a wedge 115 member between and engaging said arms and operated by the handle to move the jaws into block gripping position.

4. A machine for shaping the breast and a convex face of the shank of a wooden heel, 120 comprising, in combination, a rotary cutter having external teeth formed to shape the breast and a convex face of the shank, a table for supporting a heel block, a pair of jaws mounted on the table, a handle pivotally connected to the table, and a wedge member operated on the handle and having surfaces for moving said jaws to center the block on the table and surfaces for then moving the jaws 125 to grip the block.

5. A machine for shaping the breast and a convex face of the shank of a wooden heel, comprising, in combination, a rotary cutter having teeth formed to shape the breast and a convex face of the shank, a table for supporting a heel block and having an abutment, a pair of jaws mounted on the table, a presser for engagement with the block and having a lever pivotally connected to the table, and a handle pivotally connected to the table having a pair of cams thereon, one for causing the jaws to grip the block and the other for rocking the lever to cause the presser to engage the block. 10
15. 6. A machine for shaping the breast and a convex face of the shank of a wooden heel, comprising, in combination, a rotary cutter having teeth formed to shape the breast and a convex face of the shank, a table for supporting a heel block and having an abutment, means for centering and gripping the block on the table, means for pressing the block against the abutment, and a handle having means for operating the gripping and pressing means. 20
25. 7. A machine for shaping the breast and a convex face of the shank of a wooden heel, comprising, in combination a rotary cutter having teeth formed to shape the breast and a convex face of the shank, a table for supporting a heel block, means for centering and gripping the block, a presser for engagement with the back of the block, a handle, and means operated by the handle for causing the gripping means to center the block, the presser to engage the block, and the gripping means to grip the block, in the order named. 30
35. 8. A machine for shaping the breast and a convex face of the shank of a wooden heel, comprising, in combination, a rotary cutter having teeth formed to shape the breast and a convex face of the shank, a support, an apron pivotally mounted on the support, a table carried by the apron for supporting a heel block, means for securing the block to the table, and a handle for rocking the table and block about the point of pivotal connection of the apron with the support, thereby to shape the breast and shank face. 40
45. 9. A machine for shaping the breast and a face of the shank of a wooden heel, comprising, in combination, a rotary cutter having teeth formed to shape the breast and a face of the shank, a support, an apron pivotally connected to the support, a table carried by the apron for supporting a heel block, means for securing the block to the table, and a handle pivotally connected to the table adapted to rock in one plane to cause the gripping means 50 to grip and release the block, said handle being adapted to rock in a plane transverse to said first-named plane to rock the table about its point of pivotal connection with the support, thereby to cause the cutter to shape the breast and shank face. 55
10. A machine for shaping the breast and a convex face of the shank of a wooden heel, comprising, in combination, a rotary cutter having teeth formed to shape the breast and a convex face of the shank, a support, a table pivotally connected to the support, means for holding a heel block on the table, and a handle movable to cause the holding means to hold and release the block and movable to cause the table to rock about its point of pivotal connection with the support, thereby to feed the block past the cutter. 60
15. 11. A machine for shaping the breast and a convex face of the shank of a wooden heel, comprising, in combination, a rotary cutter having teeth formed to shape the breast and a convex face of the shank, a support having a guideway, a slide in the guideway having a pivotstud, an apron pivotally mounted on said stud, a table carried by the apron for supporting the heel block adjacent to the cutter, means for securing the heel block on the table, and means for adjusting the slide in the guideway to vary the distance of the pivot stud from the cutter. 65
20. 12. A machine for shaping the breast and a convex face of the shank of a wooden heel, comprising, in combination, a rotary cutter having teeth formed to shape the breast and a convex face of the shank, a support having a guideway, a slide in the guideway having a pivot stud, an apron pivotally mounted on said stud, a table carried by the apron for supporting the heel block adjacent to the cutter, means for securing the heel block on the table, and a screw shaft for adjusting the slide in the guideway, thereby to vary the distance of the pivot stud from the cutter. 70
25. 13. A machine for shaping the breast and a face of the shank of a wooden heel, comprising, in combination, a rotary cutter having teeth formed to shape the breast and a face of the shank, a support having a guideway, a slide in the guideway having a pivot stud, an apron pivotally mounted on said stud, a table carried by the apron for supporting the heel block adjacent to the cutter, means for securing the heel block on the table, and means for adjusting the slide in the guideway to vary the distance of the pivot stud from the cutter without varying the distance of the table from the cutter. 75
30. 14. A machine for shaping the breast and a face of the shank of a wooden heel, comprising, in combination, a rotary cutter having teeth formed to shape the breast and a face of the shank, a support having a guideway, an apron having a guideway, a slide in the support guideway having a pivot stud projecting into the apron guideway, a slide on the stud in the apron guideway, a screw shaft for adjusting the support slide in its guideway, a screw shaft connecting the apron slide with the apron, and a table carried by the apron for supporting a heel block adjacent 80

to the cutter, said screw shafts being operable to vary the distance of the pivot stud from the cutter without varying the distance of the table from the cutter.

5 15. A machine for shaping the breast and a face of the shank of a wooden heel, comprising, in combination, a rotary cutter having teeth formed to shape the breast and a face of the shank, a hanger plate having a guideway, a slide in the guideway, a screw shaft on said plate threaded to the slide, an apron having a guideway, a slide in the apron guideway pivotally mounted on the stud, a screw shaft connecting the apron with its slide, a 10 table carried by the apron for supporting a heel block, a pair of gears on the screw shafts, and a handle for rotating said gears to vary the distance of the pivot stud from the cutter.

16. A machine for shaping the breast and a convex face of the shank of a wooden heel, comprising, in combination, a rotary cutter having teeth formed to shape the breast and a face of the shank, a support, a hanger plate pivotally connected to the support, means to hold the hanger plate in vertical position in forming a flat breast and in positions inclined to the vertical in forming concaved breasts, an apron pivotally connected to the hanger plate, a table pivotally connected to the apron for supporting the heel blank adjacent to the cutter, means to hold the table at different angles with respect to the cutter, thereby to vary the angle between the breast and convex face of the shank, means for securing the heel block on the table, and a handle connected to the table for rocking the apron and table about the point of pivotal connection of the table with the hanger plate.

17. A machine for shaping the breast and a face of the shank of a wooden heel, comprising, in combination, a rotary cutter having teeth formed to shape the breast and a face of the shank, and means for supporting and feeding a heel block relatively to the cutter including a table and means for angularly adjusting the relation of the table to the cutter to vary the angle of the breast with the shank, and means for bodily adjusting the support, that adjustment for variation of the angle shall not vary the thickness of the shank.

18. A machine for shaping the breast and a face of the shank of a wooden heel, comprising, in combination, a rotary cutter having teeth formed to shape the breast and a face of the shank, a table for supporting a heel block adjacent to the cutter, means for securing the heel block on the table, and means for marking a face of the heel block on the table to assist proper location of the block in a machine for performing a subsequent operation thereon.

19. A machine for shaping the breast and a face of the shank of a wooden heel, comprising, in combination, a rotary cutter having

teeth formed to shape the breast and a face of the shank, a table for supporting a heel block adjacent to the cutter, jaws for gripping the block and holding the same on the table, a handle, means operated by the handle for moving the jaws to grip the block, and means operated by the handle for marking a face of the block.

20. A machine for shaping the breast and a face of the shank of a wooden heel, comprising, in combination, a rotary cutter having teeth formed to shape the breast and a face of the shank, a table for supporting a heel block adjacent to the cutter, jaws for gripping the block on the table, a handle for operating said jaws, a pair of marker pins projecting through holes in the table, and means operated by the handle for causing said pins to make indentations in a face of the block.
